CLAIM

The ornamental design for scissors, as shown and described.

DESCRIPTION

FIG. 1 is a front elevational view of the scissors showing my new design;

FIG. 2 is a bottom plan view thereof;

FIG. 3 is a top plan view thereof;

FIG. 4 is a rear elevational view thereof;

FIG. 5 is a side elevational view thereof, looking from the right side of FIG. 1; and,

FIG. 6 is a side elevational view thereof, looking from the left side of FIG. 1.

The broken lines shown on the drawings are for illustrative purposes only and form no part of the claimed design.

1 Claim, 2 Drawing Sheets

FIG. 2 is a bottom plan view of the scissors.

FIG. 3 is a top plan view of the scissors.

FIG. 4 is a rear elevational view of the scissors.

FIG. 5 is a side elevational view of the scissors, looking from the right side.

FIG. 6 is a side elevational view of the scissors, looking from the left side.

FIG. 1

FIG. 3

FIG. 2

FIG. 4

FIG. 5

FIG. 6
